CORD WOOD SPLITTER

Warren W. Ebbinghaus, 2028 Warm Springs Ave.,
Boise, Idaho 83702

Filed Feb. 27, 1975, Ser. No. 553,458

Term of patent 14 years

Int. Cl. D15—09

U.S. CL. D55—1 A

FIG. 1

FIG. 2

FIG. 3

FIG. 4

FIG. 5

FIG. 6

FIG. 1 is a side elevation of a cord wood splitter in accordance with my new design;

FIG. 2 is a side elevation of the opposite side;

FIG. 3 is a front elevational view thereof;

FIG. 4 is a rear elevational view thereof;

FIG. 5 is a top view thereof; and

FIG. 6 is a bottom view thereof.

I claim:

The ornamental design for a cord wood splitter, as shown.
